**ANTENNA MOUNTING FIXTURE WITH
LOADING COIL**

John B. Roll, Plainfield, N.J., assignor to DPZ Corporation, New York, N.Y., a corporation of New York
Filed Sept. 27, 1962, Ser. No. 226,611
7 Claims. (Cl. 343—749)

This invention relates to radio antennae and more particularly to antennae of relatively simple, sturdy construction having a fixed inductance coil incorporated in the circuit.

It is an object of the invention to provide a simple, strong antenna construction.

It is a further object to provide an antenna construction in which various components are permanently united by insulating material cast in place around them.

It is still a further object to produce an antenna structure incorporating a removable inductance coil assembly allowing the use of several such coils of varying inductance depending upon the frequency of the signal being received.

Still further objects of the invention will appear from the following description, in which—

FIG. 1 is a partial cross sectional view of an antenna structure during assembly of its parts;

FIG. 2 is a partial cross sectional view of an assembled antenna structure;

FIG. 3 is a partial view of an assembled antenna structure;

FIG. 4 is an enlarged cross sectional view on plane 4—4 of FIG. 3;

FIG. 5 is a partial cross sectional view corresponding to that in FIG. 4 of an alternate antenna construction;

FIG. 6 is a perspective view of a short-circuiting sleeve for use in the construction of FIG. 5;

FIG. 7 is a view corresponding to that of FIG. 5 showing an alternate coil in place; and

FIG. 8 is a perspective view of the alternate coil of FIG. 7.

FIG. 1 shows a portion of a coaxial cable 10 comprised of an inner conductor 11, an insulation layer 12, and woven wire shielding braid 13. During assembly the cable is passed through central bore 14 in base mounting screw 15 and end 16 of the shielding braid is spread away from the insulation layer to form the flared opening 17. Tapered ferrule wedge 18 is passed down over the upper end of the insulation layer, which makes a sliding fit with axial hole 19 therein.

The coaxial cable and the base mounting screw are then locked together by forcing the ferrule wedge downward into the central bore 14 of the base mounting screw to the position shown in FIG. 2. The central bore is comprised of a cylindrical segment 20 and a flared segment 21, the former adapted to loosely clasp the coaxial cable and the latter, in conjunction with ferrule wedge 18, to grasp tightly the shielding braid. This construction holds the coaxial cable securely without the necessity of knotting it, pinching the insulation, or putting stress on the inner conductor 11.

The assembly of FIG. 2 is incorporated into the finished structure of FIGS. 3 and 4 by casting molded base 22 around head 23 of the base mounting screw. Grooves 24 in head 23 give the cast material a good grip on the head. Since the molded base serves both as an insulator and as a load-bearing mechanical component it has been found that this element is best made of a high strength plastic such as nylon. The upper end 25 of the molded base grips antenna connection socket 26 which bears peripheral grooves 27 to insure a permanent connection. Bore 28 in socket 26 makes a force fit with the bottom

2

end 29 of a conventional tubular antenna rod 30, which may extend upward to any convenient height.

Prior to the casting step, the antenna connection socket 26 and the base mounting screw 15 are placed so as to project into the cavity of a suitable mold (not shown). The end 31 of the inner conductor is bent to one side and extends into the wall of the mold cavity, so that a short length projects from the molded base. Connection between the antenna rod 30 and the inner conductor 11 is effected through an inductance coil comprised of inductance wire 32, wrapped in a helix around the molded base. One end of the inductance wire is provided with a loop 33 soldered thereto. The loop is maintained in electrical contact with end 31 of the inner conductor by means of lower screw 34 which is threaded into tapped hole 35 in the molded base. The inner conductor is wrapped around the lower screw, which presses it against the loop in the inductance wire when the screw is tightened.

20 The helical turns of inductance wire may be kept in place on the molded base by suitable varnish or glue. The upper end 36 of the inductance wire is wrapped around upper screw 37, which passes through hole 38 in the molded base and is threaded into a tapped hole 39 in the antenna connection socket 26.

In use the antenna is fastened to a suitable bracket 40 by passing the base mounting screw through a mounting hole 41 in the bracket and tightening nut 42 on the threads 43 of the mounting screw.

30 The antenna described above has an inductance coil which is an integral part of the rest of the device. It is often desired to change the inductance of the coil depending on the size of the antenna rod and the frequency of the signals being received. FIGS. 5—8 show an alternate construction allowing such changes, as well as illustrating variations in the design of other components. In FIG. 5 is shown base mounting screw 44 united with a coaxial cable 45 in an assembly identical with that of FIG. 2. End 46 of the inner conductor 47 is soldered into central bore 48 of metal barrel 49. The molded base 50 is then cast about the components just described, as well as around antenna connection socket 60 which is similar to antenna connection socket 26 of FIG. 4.

45 In the embodiment of FIGS. 5—8 a cylindrical sleeve of insulating material is provided to slip loosely over the molded base 50. The cylindrical sleeve is held in place by a lower screw 52 which passes through a hole 53 in the sleeve and a hole 54 in the molded base and screws into tapped hole 55 in metal barrel 49. Upper screw 56 passes through hole 57 in the cylindrical sleeve, hole 58 in the molded base, and into tapped hole 59 in antenna connection socket 60, the latter being similar in construction to antenna connection socket 26 of FIG. 4.

55 In FIGS. 5 and 6 sleeve 51 is equipped with a metal shunt 61 extending between the upper screw 56 and the lower screw 52. Thus, no inductance is put into the circuit by the sleeve. FIGS. 7 and 8 show a second sleeve 62 which may be slipped over molded base 50 in place of sleeve 51 when it is desired to add an inductance coil in series with the antenna. Sleeve 62 is provided with an inductance wire 63 wound helically on its outer surface and held in place with varnish or glue. The ends of the inductance wire are fastened to the sleeve by metal rivets 64 and 65 which have central holes through which the upper and lower screws pass.

FIGS. 5 and 7 show a second type of antenna rod. Antenna rod 66 has a widened lower end 67, the central bore 68 of which fits over the outside of antenna connection socket 60. The fit may be a force fit if a permanent connection is desired, or it may be a loose fit with a setscrew 69 holding the parts together.

The antenna described is simple and rugged in its construction. The molded nylon base completely encloses and seals the open end of the coaxial cable and prevents loosening of the ferrule wedge 18. The inductance coil is exposed so that the number of turns therein may be varied, either by changing a removable sleeve or by stripping off part of the inductance wire from the outside of the molded base and reconnecting the remainder. 5

The following is claimed:

1. An antenna structure comprising 10
  - (a) a base mounting screw having a longitudinal central bore, a threaded shank, and a head;
  - (b) a coaxial cable passing upward through the central bore of the base mounting screw and having an inner conductor, an insulating layer surrounding the inner conductor, and a shielding braid surrounding the insulating layer, the upper end of the inner conductor projecting beyond the head of the base mounting screw; 15
  - (c) a ferrule wedge having an axial hole, the insulating layer and the inner conductor of the coaxial cable passing upward through the axial hole and the ferrule wedge lying at least partly inside the shielding braid, said ferrule wedge forcing the shielding braid outward against the wall of the central bore of the base mounting screw and thus cooperating with said wall to grip the shielding braid tightly; 20
  - (d) an antenna connection socket adapted to couple to an antenna rod;
  - (e) a molded base of insulating material molded about and securely gripping the head of the base mounting screw and partially enclosing the upper end of the inner conductor, said molded base partially surrounding and securely gripping the antenna connection socket while maintaining said antenna connection socket out of direct electrical contact with said base mounting screw; and 30
  - (f) electrical connecting means for carrying current between the upper end of the inner conductor and the antenna connection socket.
2. The antenna structure of claim 1 wherein the electrical connecting means comprises an inductance coil wound around the outside of the molded base. 40
3. The antenna structure of claim 1 wherein the electrical connecting means comprises a demountable sleeve adapted to surround the molded base and an inductance coil wound around said sleeve. 45
4. The antenna structure of claim 1 wherein the electrical connecting means comprises a demountable sleeve adapted to surround the molded base and a shunt mounted on said sleeve. 50
5. The antenna structure of claim 1 wherein the molded base is formed of nylon.

6. An antenna structure comprising

- (a) a base mounting screw having a substantially cylindrical shank with external threads thereon, a head at one end of the shank, indentations on the head, and a central bore, said central bore being comprised of a cylindrical portion within the shank and a tapered portion at least partially within the head, said tapered portion flaring outward;
- (b) a coaxial cable having an inner conductor, an insulating layer surrounding the inner conductor, and a shielding braid surrounding the insulating layer, the upper end of the inner conductor extending past the upper ends of the insulating layer and shielding braid;
- (c) a ferrule wedge having a cylindrical axial hole surrounding the insulating layer adjacent the upper end thereof and a tapered outer surface contacting the inner surface of the shielding braid adjacent the upper end thereof and forcing the shielding braid outward against the tapered portion of the central bore of the base mounting screw;
- (d) an antenna connection socket having an axial bore and indentations in its outer surface;
- (e) an elongated plastic molded base of substantially circular cross section in a plane perpendicular to its longitudinal axis, the material in said base adjacent the lower end thereof surrounding and firmly gripping the head of the base mounting screw and the material in said base adjacent the upper end thereof surrounding and firmly gripping the surface of the antenna connection socket bearing the indentations; and
- (f) inductance wire coil surrounding the molded base and having one end electrically connected to the inner conductor and the other end electrically connected to the antenna connection socket.

7. The antenna structure of claim 6 comprising a removable cylindrical sleeve surrounding the molded base and bearing on its outer surface the inductance wire coil. 40
